FISHING REEL

James H. Hopper, 1 Taylor Road, Hazardville, Conn.

Filed Oct. 21, 1965, Ser. No. 87,682

Term of patent 7 years

(Cl. D31—4)

I claim:

The ornamental design for a fishing reel, substantially as shown and described.
